UNITED STATES PATENT OFFICE.

JOHN H. WILLEMS, OF KENOSHA, WISCONSIN.

ADJUSTABLE BED-SPRING.

1,229,561.

Specification of Letters Patent. Patented June 12, 1917.

Application filed August 5, 1916. Serial No. 113,220.

To all whom it may concern:

Be it known that I, JOHN H. WILLEMS, a citizen of the United States, and resident of Kenosha, in the county of Kenosha and 5 State of Wisconsin, have invented certain new and useful Improvements in Adjustable Bed-Springs; and I do hereby declare that the following is a full, clear, and exact description thereof.

10 The present invention relates to new and useful improvements in bed springs, more particularly of that type including a series of spring coils, and an intersecting series of tie members.

15 Bed springs of this nature require to be tightened from time to time, and the usual method of tightening is to draw the springs longitudinally. This method, however, does not provide for independent tightening of 20 the springs, particularly as this would procure distortion of the tie members, and possesses other disadvantages in practice. It is primarily an object of the present invention to provide a means for individually 25 tightening the coils of a bed spring, and it is more specifically an object to procure a tension adjustment of the coils by axial twisting manipulation thereof, in a manner, however, which does not interfere with the 30 disposition of the tie members of the spring nor with their connection with the coils.

In connection with the adjustment of the coils, it is further an object to provide a means for securing the ends of the coils to 35 the frame in a manner wherein their extremities are held against possible detachment or engagement with the bed clothes, yet in a manner permitting ready detachment of the coil ends for twisting manipulation of the coil ends for twisting manipulation thereof.

A further and more general object of the invention resides in the provision of a bed spring wherein the sagging tendency of the coils is reduced to a minimum.

45 A still further object resides in the provision of tie members which are interwoven with the coils in the formation of the spring fabric to materially reduce the cost of manufacture thereof and to produce a structure 50 of maximum strength and durability.

With the above and other objects and advantages in view, the invention resides more particularly in the novel combination, arrangement and formation of parts more particularly hereinafter described and pointed out in the appended claims.

In the drawings:

Figure 1 is a plan view of a portion of a bed spring embodying the present invention.

Fig. 2 is a plan view of the entire bed 80 spring on a reduced scale.

Referring now more particularly to the accompanying drawings 5 and 6 designate respectively the side and end rails of the usual frame of the bed spring. In the present structure the spring coils 7 extend transversely in spaced relation across the frame and are secured to the side rails, in a readily detachable manner, by passing their end convolutions through a series of openings 8 70 in said side rails adjacent their inner edges, the extremities of said end convolutions being extended inwardly and engaged under the top portions of the convolutions whereby possible accidental displacement of the coils 75 is prevented and further whereby said extremities are held against such engagement with bed clothes or the like as might tear them. The extremities of said end convolutions are preferably inserted through 80 their openings from the under side of the rails to permit them to be more readily placed beneath the top portions of the convolutions. Extending longitudinally of the frame and secured in openings 9 in the end 85 rails 6 are a series of tie members 10 each comprising a pair of wires twisted together throughout with their portions adjacent the intersections of the coils 7 spaced apart to form loops 11 each loosely receiving one side 90 of the adjacent convolution of a coil. The tie members may thus be readily and most economically interwoven with the coils to form the body fabric of the spring.

To adjust the tension of the springs, they 95 are detached from one of the sills and twisted axially and then again secured to the rail. In this operation the convolutions of the coils move freely through the loops 10, to distribute the tension equally along the 100 lengths of the coils, and thus neither the positions of the tie members nor their connections with the coils are affected upon independent tension adjustment of the coils. I am aware that it has been heretofore contemplated to adjust the tension of bed 105 spring coils by twisting them axially, the adjusting feature of my invention resides more particularly in the compensating connections between the coils and the tie members, and although it has been heretofore contemplated to connect the coil springs of 110

a bed by independent links which form loose tie members after a fashion, such an arrangement would not be practical in the present arrangement due to the differential tension at times afforded different portions of each coil which would tend to displace the links along the coils, and I find the provision of a continuous tie member provided with spaced portions holding the coils in a manner permitting rotation thereof, to be essential in the present structure.

A further advantageous feature of the present structure resides in the provision of transverse spring coils and longitudinal tie members secured to the ends of the frame and connected with the intersecting portions of the coils whereby the sagging tendency present in that type of structure including longitudinally extending coils is prevented.

20 I claim:

1. A bed spring of the class described comprising in combination, a frame, a series of transversely extending coil springs connected at their opposite ends with the opposite rails of the frame, said springs being adapted to be axially twisted to vary the tension thereof, and a series of longitudinally extending flexible, non-resilient tie members connected with the frame and the springs to prevent excessive sagging of the latter, each of said members being formed from a pair of twisted wires, the portions engaging said coil springs being spaced apart to form loops to loosely receive the

same, the position of said tie members being 35 unchanged by varying the tension of said coil springs.

2. A bed spring of the class described comprising in combination, a frame having a series of openings formed in its opposite 40 rails adjacent the inner edges thereof, a series of transversely extending coil springs having their opposite end convolutions engageable through the openings in the side rails from the under side thereof, their 45 extremities being directed inwardly beyond the adjacent edges of the rails and disposed under the upper portions of the said end convolutions for the purpose set forth, the tension of said springs being varied by axially twisting the same, and a series of longitudinally extending tie members disposed through the openings in the end rails, each being formed from a pair of twisted wires, the portions adjacent the convolutions being 50 spaced apart to form loops for loosely receiving said springs, the position of said tie members being unchanged by varying the tension of said coil springs.

In testimony that I claim the foregoing 55 I have hereunto set my hand at Kenosha, in the county of Kenosha and State of Wisconsin, in the presence of two witnesses.

JOHN H. WILLEMS.
